UNITED STATES PATENT OFFICE.

CLARENCE LA FAYETTE STOCKS, OF BLUE RIDGE, GEORGIA.

PROTECTIVE HELMET.

1,199,629.

Specification of Letters Patent. Patented Sept. 26, 1916.

Application filed October 1, 1915. Serial No. 53,504.

To all whom it may concern:

Be it known that I, CLARENCE L. STOCKS, a citizen of the United States, and a resident of Blue Ridge, in the county of Fanning and State of Georgia, have invented an Improvement in Protective Helmets, of which the following is a specification.

This invention is an improvement in wearing apparel, and has particular reference to 10 a helmet adapted to protect the head of the wearer against injury due to severe falls or blows.

Briefly stated, the invention includes a resilient supporting ring adapted to fit over 15 the head of the wearer and having connected thereto a skull cap, a padded sweat band and, at intervals, a plurality of vertically arranged guards the upper ends of which are bent to converge and are secured 20 together whereby to form a protective cushion for the head so that the shock of a blow will be effectively distributed. In order to reinforce the vertical guards and provide a further protection there is also employed a 25 plurality of annular horizontally arranged guards which are connected to said vertical guards in spaced relation.

An object of the invention is to provide a 30 novel means of adjusting the size of the supporting ring in order to accommodate different sized heads, the skull cap and sweat band being so secured to said ring as not to interfere with said adjustment. The 35 vertical guards are also connected to said ring in a manner to permit of relative movement between the same when adjusting the latter.

Another object is the provision of vertically arranged guards which are formed so 40 that the portions thereof most likely to receive a blow or shock are spaced a sufficient distance from the head to prevent the same being injured.

The inventive idea involved is capable of 45 receiving a variety of mechanical expressions, one of which, for the purpose of illustrating the invention, is shown in the accompanying drawings, in which—

Figure 1 is a side elevation of the invention 50 showing the application thereof. Fig. 2 is a top plan view, a part being broken away. Fig. 3 is an enlarged fragmentary vertical longitudinal sectional view. Fig. 4 is a transverse section on the line 4—4 of Fig. 3. 55 Fig. 5 is a similar section on the line 5—5 of Fig. 3. Fig. 6 is a fragmentary perspective

view of one end of one of the vertically arranged guards showing the means for connecting the same to the supporting ring.

The device is particularly adapted to be 60 worn for the protection of infants in learning to walk or for persons engaging in hazardous pleasures or occupations, and comprises a main supporting element 10 preferably made of resilient metal and in the 65 form of a split ring. This element is provided around its upper and lower edges with a plurality of small openings 11, the upper openings being adapted to receive stitches for securing the lower edge of a skull cap 70 12 to said element, said cap being adapted to engage closely over the wearer's head. The lower row of openings is used for the purpose of securing one edge of a padded sweat band 13 to said element. The ring 10 75 is made adjustable in order that it may be fitted to different sized heads and for this purpose one end of said ring is slotted as indicated at 14, said slot being adapted to receive the shank of a screw 15 therein having a nut 16 for the purpose of securing the ends of the ring together after the same have been adjusted to the desired position. The slotted end of the ring is reduced upon 80 its lower edge as indicated at 16' and this 85 edge together with the upper edge of said ring is bent away from the adjacent end of the ring 10, as best illustrated in Fig. 4, to provide the flanges 17 so that when adjusting the ring the portions of the skull 90 cap, secured to the outer end of the ring, will occupy the space between the flanges 17 and said outer end whereby any jamming, which might otherwise occur when 95 adjusting said ring, will be prevented.

At regular intervals around the ring 10 the same is provided with a plurality of slots 18, each of which is adapted to receive a guide 19 secured in spaced relation to one end of a vertically arranged guard 20 which 100 is preferably made of an elongated strip of resilient metal. The lower edge of each slot 18 is adapted to engage between the guide 19 and a guard 20 so that the latter is retained in position and the slot is made of 105 sufficient length to permit of an adjustment of the ring 10 which adjustment is made relative to said guards. Each of the guards depends a considerable distance below the ring 10 and is then bent outwardly and upwardly so that the outer portion of the 110 guard will be spaced a considerable distance

from the wearer's head. The uppermost portions 21 of the guards are then curved to conform substantially to the shape of a head and the upper ends meet and are secured to a plate 22 by means of rivets 23 thus forming a crown portion for the helmet. When in position on the wearer's head one of the vertical guards depends directly in front of the nose so that the sight is unimpaired. 5 Obliquely arranged guards may also be employed in connection with the vertical and horizontal guards. In order to further protect the head and provide reinforcement for the several vertically arranged guards 20 10 there are also provided a plurality of horizontally arranged guards 24 in the form of annular rings secured to the outer faces of the vertical guards and arranged in superposed relation, the bottom edge of the upper 15 20 guard being preferably in horizontal alinement with the upper edge of the ring 10 and the upper edge of the lower guard being in similar alinement with the lower edge of said ring 10.

25 It will be seen from the foregoing description taken in connection with the accompanying drawings that the invention contemplates providing an improved helmet which will effectively protect the head of the 30 wearer against the shocks caused by blows or accidental falls.

What is claimed is:—

35 1. A helmet comprising a main supporting member for encircling the wearer's head, a plurality of guards connected to said member, and means for adjusting said supporting member relative to said guards in order to vary the diameter of said member.

40 2. A helmet comprising a main supporting element, a plurality of guards connected thereto, other guards mounted transversely to the first-named guards, and a skull cap carried by said supporting element.

45 3. A helmet comprising a main supporting member for encircling the wearer's head, and a plurality of vertically arranged guards having intermediate portions extending below said member and their lower extremities secured thereto for protecting the lower portion of the head.

50 4. A helmet comprising a main supporting element, a plurality of guards connected thereto, other guards mounted transversely to the first-named guards, a skull cap carried by said supporting element, and a padded sweat band secured to said supporting element.

55 5. A helmet comprising a main supporting element adapted to encircle the wearer's head, a plurality of guards connected to said element, other guards secured to the first-named guards and arranged transversely thereof, and means for adjusting

said supporting element relative to said guards in order to vary the diameter of the 65 former.

6. A helmet comprising a split supporting ring, one end of which is reduced and provided with a slot, said reduced end being provided with lateral flanges upon its upper 70 and lower edges whereby portions of said end are spaced from the opposite end of the ring, a skull cap secured to said ring and having a portion thereof interposed between one of said flanges and the adjacent face of said 75 ring, a sweat band also secured to said ring, and a plurality of resilient guards connected to said ring and adapted to form a crown for the helmet.

7. A helmet comprising a split supporting ring, one end of which is reduced and provided with a slot, said reduced end being provided with lateral flanges upon its upper and lower edges whereby portions of said end are spaced from the opposite end 85 of the ring, a skull cap secured to said ring and having a portion thereof interposed between one of said flanges and the adjacent face of said ring, a sweat band also secured to said ring, a plurality of resilient guards 90 connected to said ring and adapted to form a crown for the helmet, said guards including strips the upper ends of which converge, and a plate for securing said upper ends together.

95 8. A helmet comprising a main supporting member for encircling the wearer's head, a plurality of vertically arranged guards having intermediate portions extending below said member and their lower 100 extremities secured thereto for protecting the lower portion of the head, and other horizontally arranged guards secured to the first-named guards.

105 9. A helmet comprising a main supporting element having a plurality of slots therein, a guard associated with each slot and having a guide connected thereto adapted to engage one edge of said slot to permit of an adjustment of said element, and means 110 for adjusting said element to vary the diameter thereof.

115 10. A helmet comprising a main supporting element having a plurality of slots therein, a guard associated with each slot and having a guide connected thereto adapted to engage one edge of said slot to permit of an adjustment of said element, means for adjusting said element to vary the diameter thereof, and other guards secured to the 120 first-named guards and arranged transversely thereto.
